UNITED STATES PATENT OFFICE.

CHARLES A. LUNDY, OF RENO, NEVADA, ASSIGNOR TO LUNDY GAS ENGINE COMPANY,
OF RENO, NEVADA, A CORPORATION OF NEVADA.

GAS-ENGINE.

1,210,089.

Specification of Letters Patent. Patented Dec. 26, 1916.

Original application filed October 25, 1915, Serial No. 57,710. Divided and this application filed April 18, 1916. Serial No. 91,908.

To all whom it may concern:

Be it known that I, CHARLES A. LUNDY, a citizen of the United States, residing at Reno, in the county of Washoe and State of Nevada, have invented certain new and useful Improvements in Gas-Engines, of which the following is a specification.

This is a division of my certain pending application Serial Number 57,710, filed October 25, 1915.

My invention relates to that class of gas-engines in which the cylinder is mounted for rotation on its axis thereby carrying its port, in timely succession, into registry with fixed 15 charging, exploding and exhausting connections.

My invention consists in the novel air-cooling means which I shall now fully describe by reference to the accompanying drawings in which—

Figure 1 is an elevation of my gas-engine. Fig. 2 is a plan of the same, broken in part. Fig. 3 is an enlarged view, partly in elevation and partly in section, showing one cylinder complete and a portion of another cylinder. Fig. 4 is a horizontal cross-section through the valve-area of the cylinder, taken on the line $x-x$ of Fig. 5. Fig. 5 is a vertical cross section of the same on the line $y-y$ of Fig. 4. Fig. 6 is a section in the line $z-z$ of Fig. 3, showing the locking and adjusting means of the revoluble cylinder bearing. Fig. 7 is an elevation of the packing-sleeves of the valve-area.

As the air-cooling means or systems of my present application comprises cylinders which rotate on their axes, I herein illustrate and describe cylinders which have this function, and though I show and explain in detail the manner of mounting such cylinders and the valve control of their ports, it will be understood that these details as far as this application is concerned indicate only preferred forms and are intended to disclose an operative device of this nature, said details constituting features of novelty remaining and claimed in my application of which this is a division.

1 is the crank case, which is also the bed 50 of the engine.

2 are the cylinders. I have here shown a four cylinder engine, though it will be understood that the engine may have one or any number of cylinders. Each cylinder is rev-

clubly locked to the bed by a connection 55 which will enable it to resist end-thrust, due to explosion, and will adapt it for rotation on its axis. This connection is shown in Fig. 3, and is as follows. As all the cylinders are alike, a description in the singular 60 number will be simplest. Extending from the crank-case is an annular shell or housing 3 which forms the seat for the cylinder. This housing is open at both ends, and has formed on its inner surface, near its upper 65 or outer end, an inwardly extending rib or lug 4, which as shown in Fig. 6, is in two spaced opposite sections. Closely fitted upon the exterior of the lower portion of the cylinder is a spiral gear 5. The fitting 70 is by means of threads 6 on the cylinder, the gear being threaded on its inner diameter down to a shoulder 7, and said gear is screwed up on the threads 6 of the cylinder to this shoulder, as seen in Fig. 3. The portion of the gear above the shoulder is formed as a thrust bearing race 8 for the ball bearings 9.

10 is a lock-ring which on account of its lower flange 10' spaced in sections, as seen in 80 Fig. 6, clamps in place by a partial turn on or under the rib or lug 4 on the inner surface of the cylinder-seat housing 3.

11 is an adjusting-ring threaded into the lock-ring 10, and formed on its lower surface with the complementary race 12 for the ball bearings 9. The inner surface of the adjusting-ring 11 is hollowed out for a packing space 13.

The seat housing 3 has at its lower or inner 90 end a flange 14 upon which rests a suitable lower anti-friction bearing which in its best form comprises the inner ring 15 freely fitted around the cylinder, and supporting the spiral gear 5, the outer ring 16 resting on 95 the flange 14 and having an inclined inner surface, and the taper rolls 17 between the two rings.

The cylinder 2 has a relatively long slender neck 2' which forms a valve. This valve 100 neck extends directly and centrally from the main body or piston-area of the cylinder, and is open at both ends. It forms not only the valve member of the valve area or system but also the compressing and firing 105 chamber directly over the center of the piston. In the wall of the neck 2' of the cylinder is made the single port 18. (See Fig. 4).

Around the lower portion of the neck 2' in grooves therein are seated the packing rings 19 in any suitable number, say four, for example. Upon the top of the neck is 5 screwed down the annular lock-nut 20, in a groove in the face of which is seated a packing ring 21. The port 18 in the cylinder neck lies in the area between the uppermost packing ring 19 and the lower surface of the 10 nut 20, and around this area is fitted a set or series of packing-sleeves 22. These sleeves may be in any desired number; I have, for illustration, shown two. They are 15 nested, one within the other and interfit closely. Each sleeve is not only severed longitudinally, but the severed edges are separated by a distinct space to provide for a continuance of fit under all conditions of expansion and contraction. These spaces are 20 designated by 23, and they are best arranged in the two sleeves opposite each other, as seen in Fig. 4. These sleeves while they interfit closely do not normally closely fit the neck of the cylinder, that is to say, the inner 25 sleeve loosely fits the neck being separated from the exterior surface of said neck by a distinct space, as shown in Figs. 4 and 5, at 24. The sleeves contract inwardly when 30 heated and expanding, thus lessening their diameter on the inside and retaining the same closeness to the member on the outside, thus preventing a loss of gas, and avoiding binding and cutting.

The sleeves 22 fit between the shoulders 35 formed by the uppermost packing ring 19 and the lower surface of the lock nut 20, as best seen in Fig. 5, and they are locked or pinned to the neck, as, for example, at 22', Figs. 4 and 5, so that they rotate therewith. 40 Through the walls of the sleeves is made a port 26 which permanently registers with the port 18 of the cylinder neck, as shown in Fig. 4.

27 is a fixed valve-seat-sleeve. It is a cylindrical shell closed at the top except for a spark-plug hole 28 threaded in the center thereof, as in Fig. 5. It has the inlet port 29 cut in one side and the exhaust port 30 cut in the other side. It slips down over the 50 cylinder valve neck 2', fitting firmly against the face of the packing ring 21 in the nut 20, the faces of the lower set of packing rings 19, and the outer surface or face of the outermost packing sleeve 22, as shown in 55 Fig. 5, thus preventing the passing of any air or gas mixture by the valve or packing rings or sleeves.

The valve-seat-sleeve 27 is held fixed and 60 non-rotatable by the cylinder head or valve chamber 31 which fits over it. This head has a top flange 32 overlapping upon the upper end of the sleeve valve 27 and lock pins 33 through this flange into the sleeve to connect the two. A packing lock nut 34 is 65 fitted to the lower ends of the sleeve and

head. The head 31 has an intake passage 35 which registers with the inlet port 29 of the sleeve 27, and an exhaust port 36 which registers with the exhaust port 30 of the sleeve.

70 It will now be seen that as the aligned ports 18 and 25 of the cylinder valve neck and its packing sleeves rotate they will alternately open and close the aligned inlet and exhaust ports and passages of the fixed valve-seat-sleeve and head. All these ports are laid in proper width and separated to provide the correct timing of a four cycle motor.

75 To properly support and hold the valve-chamber head 31 stationary, said head has 80 extended lugs 37 from which tie-rods or bolts 38 pass down to lugs 39 on the cylinder-seat-housing 3 of the crank-case, as seen in Fig. 1.

In case the seat-housing 3 be made as a 85 separate piece from the crank-case, it may be made with other lugs 40 for bolting it to the casing, as seen in Fig. 3.

90 The driving mechanism for rotating the cylinders is as follows: The seat-housing 3 has made in its face an opening 41, surrounded by a flange 42, to which the cap 43 bolts and holds the bearings 44 and the driving shaft 45 in place, and allowing the spiral pinion 46 to engage the spiral gear 5 through the opening 41. The shaft 45 may be driven by any suitable connection, as, for example, by the silent chain 47 from the crank shaft 48. The spiral gears 46 and 5 are of such ratio that the cylinder 2 100 must revolve at one half the speed of the crank shaft 48. To the crank shaft are connected the piston rods, one of which is shown by 49 in Fig. 3, and these at their other ends are connected to pistons which are not shown 105 herein.

110 The several features of the air cooling means or system may now be described. The cylinder 2 above its revoluble connection with the seat-housing 3, and below its valve neck 2', that is, in its piston-area, is provided with fins or flanges 50, helically directed and so pitched or inclined as to serve as fan blades to pull the air away from the neck 2' and its assembled parts, as the cylinder 115 revolves. These fins or flanges are in practice best cast with the cylinder.

120 The stationary valve-chamber head 31 is surrounded by a series of cooling fins or flanges 51, the upper one of which is finished with the lugs 37 for the tie-rods 38 heretofore mentioned.

125 Surrounding the whole engine is an air directing shell or housing 52. At the front end this housing is only partly open, as at 53, being closed by the wall 54 in the remaining part. At the rear end the arrangement is relatively the opposite of that at the front end, said rear end being open in part at 55 and closed in part by a wall 56, 130

the openings in front and rear being thus on opposite sides of a central longitudinal vertical plane through the housing. The current of air, therefore, which enters 5 through the opening 53 at the front end is on one side of the cylinders, which revolving into said current catch the air and pass it to the other side in line for it to pass out through the opening 55 at the rear end of 10 the housing. The current is drawn out by the suction fly wheel 57 connected with the housing 52 by a housing 57'.

The course of the air is indicated by the arrows in Fig. 2. The cylinders are timed to 15 make one complete revolution between each explosion, thus bringing every part into the same temperature of cooling air once after each heating, causing a uniform expansion of the cylinder everywhere and a uniform 20 cooling of all working parts. 58 indicates the magneto, and 59 the magneto gear housing. 60, in Fig. 1, is the oil tank, and 61 is the exhaust manifold.

In the means or system of cooling as I 25 have described, it will be seen that the rotation of the cylinders plays an essential part in that all parts and sides of the cylinder are presented uniformly and equally to the air current, which is in marked contrast to the effect upon non-rotating cylinders of an air current merely directed from one side to the other of such stationary cylinders, the latter being an imperfect and unequal cooling by the direction of the air 35 alone, while in the case of the rotating cylinders as I have described, the uniform cooling is due to the rotation of the cylinders in the current which is directed in the best course to fully and completely envelop them. 40 In this connection it will be seen also that the spirally directed fins associated with the rotating cylinders materially assist in directing the course of the air current, and thereby serve a function in addition to that of 45 merely providing an extensive radiating surface as is the case of fins upon non-rotating cylinders.

I claim:—

1. In a gas-engine having a cylinder 50 mounted for rotation on its axis and means called into timely action by said rotation for admitting and exploding a gaseous mixture and exhausting the products of explosive combustion, a housing inclosing said 55 cylinder, said housing at one end being open for receiving a current of air in line with one side of the cylinder and closed to the air in line with the other side thereof, and at its other end being open for discharging the 60 current of air in line with the second side of the cylinder and closed to the discharge of the air in line with the first side thereof.

2. In a gas-engine having a cylinder 65 mounted for rotation on its axis and means called into timely action by said rotation

for admitting and exploding a gaseous mixture and exhausting the products of explosive combustion, a housing inclosing said cylinder, said housing at one end being open for receiving a current of air in line with 70 one side of the cylinder and closed to the air in line with the other side thereof, and at its other end being open for discharging the current of air in line with the second side of the cylinder and closed to the discharge of the air in line with the first side thereof, and means associated with the cylinder for assisting in directing the current of air from one side to the other.

3. In a gas-engine having a cylinder 80 mounted for rotation on its axis and means called into timely action by said rotation for admitting and exploding a gaseous mixture and exhausting the products of explosive combustion, a housing inclosing said 85 cylinder, said housing at one end being open for receiving a current of air in line with one side of the cylinder and closed to the air in line with the other side thereof, and at its other end being open for discharging the current of air in line with the second side of the cylinder and closed to the discharge of the air in line with the first side thereof, and spirally directed fins carried 90 by the rotatable cylinder for assisting in directing the current of air from one side to the other.

4. In a gas-engine having a cylinder 95 mounted for rotation on its axis and means called into timely action by said rotation for admitting and exploding a gaseous mixture and exhausting the products of explosive combustion, a housing inclosing said cylinder, said housing at one end being open 100 for receiving a current of air in line with one side of the cylinder and closed to the air in line with the other side thereof, and at its other end being open for discharging the current of air in line with the second side of the cylinder and closed to the discharge of the air in line with the first side thereof, spirally directed fins carried by the rotatable cylinder for assisting in directing 105 the current of air from one side to the other, and a fan blower associated with said housing for inducing the flow of the air 110 there-through.

5. In a gas-engine, the combination of a cylinder mounted for rotation on its axis and having a port in its upper portion; a non-rotatable sleeve and associated non-rotatable head fitted to the upper portion of the cylinder and having inlets and exhausts with which the cylinder port is adapted 115 to successively register; a series of exterior fins carried by the non-rotatable head; a series of exterior helically directed fins carried by the rotatable cylinder about its lower portion below said head, said helically directed fins being pitched to draw the air 120 125 130

- 4
- from about the head and valve region of the cylinder; and a housing inclosing the whole of said cylinder with its associated sleeve and head, said housing at one end 5 being open for receiving a current of air in line with one side of the cylinder and closed to the air in line with the other side thereof, and at its other end being open for discharging the current of air in line with the second side of the cylinder and closed to the discharge of the air in line with the first side thereof, the spirally directed fins of the rotatable cylinder assisting in directing the current of air from one side to the other.
- 10 6. In a gas-engine, the combination of a cylinder mounted for rotation on its axis and having a port in its upper portion; a non-rotatable sleeve and associated non-rotatable head fitted to the upper portion of the cylinder and having inlets and exhausts with which the cylinder port is adapted to successively register; a series of exterior fins carried by the non-rotatable head; a series of exterior helically directed fins carried 15 by the rotatable cylinder about its lower portion below said head, said helically di-
- rected fins being pitched to draw the air from about the head and valve region of the cylinder; a housing inclosing the whole of said cylinder with its associated sleeve 20 and head, said housing at one end being open for receiving a current of air in line with one side of the cylinder and closed to the air in line with the other side thereof, and at its other end being open for discharging the current of air in line with the second side of the cylinder and closed to the discharge of the air in line with the first side thereof, the spirally directed fins of the rotatable cylinder assisting in directing the 25 current of air from one side to the other; and a fan blower associated with the housing for inducing the flow of the air therethrough.

In testimony whereof I have signed my name to this specification in the presence of two subscribing witnesses.

CHARLES A. LUNDY.
